UNITED STATES PATENT OFFICE

2,383,712

LASTING SHOES

Michele Cuozzo, Lynn, Mass.

Original application September 3, 1941, Serial No. 409,368. Divided and this application February 3, 1944, Serial No. 520,868

3 Claims. (Cl. 12—12)

This invention relates to an improvement in lasting shoes, and has for its principal object the provision of means for lasting the two shoes of a pair concomitantly in a single operation, this application being a division of the application upon which Patent No. 2,344,503 was granted on March 21, 1944.

Heretofore it has been the universal practice, so far as it is known, to last the two shoes of a pair independently. Thus there was no certainty that both shoes of a pair would be subjected to the same lasting stress and would have the same appearance when finished or would wear equally well. Moreover, the usual lasting methods, so far as factory production is concerned, ordinarily require expensive machinery and highly skilled operators. Among the advantages of the present invention are the reduction in the time consumed in lasting a pair of shoes; the provision of a very simple method which can be performed, for example, by relatively inexpensive machinery and by relatively unskilled operatives; the assurance that both shoes of a pair will be subjected to the same lasting stress and will thus have substantially the same appearance when completed and will wear substantially equally; and further a saving in upper leather since the usual lasting margin may be substantially reduced. Other and further objects and advantages of the invention will appear from the following more detailed description and by reference to the accompanying drawings in which:

Fig. 1 is a plan view of two superposed complete uppers of a pair of shoes which have been united at the vamps in accordance with this invention;

Fig. 2 is a view in side elevation of the uppers of Fig. 1 turned inside out;

Fig. 3 is a view in side elevation, with parts broken away, of the uppers of Figs. 1 and 2 assembled with the insoles upon a pair of lasts.

Fig. 4 is a cross-section taken along the line 4—4 in Fig. 3;

Fig. 5 illustrates in perspective the uppers, insoles and lasts mounted in a machine by which the vamps of the uppers are pulled over and attached to the insoles;

Fig. 6 is a longitudinal section through the machine of Fig. 5, one of the lasts with its insole and upper being removed;

Fig. 7 is a view in side elevation of a machine by which the quarters and shanks of a pair of shoes are pulled over and attached to the insoles;

Fig. 8 is an enlarged plan view of the wiping element of such machine;

Fig. 9 is a perspective view of a welt which may be assembled with the shoes;

Fig. 10 is a view similar to Fig. 4 showing such welt assembled with the uppers;

Fig. 11 is a plan view of two superposed vamps formed into a unit;

Fig. 12 is a side elevational view of a pair of lasts carrying insoles with the vamp unit of Fig. 11 attached thereto;

10. Fig. 13 illustrates two quarters joined into a unit along the lasting margin;

Fig. 14 is a side elevational view of a pair of lasts carrying insoles with the quarter unit of Fig. 13 attached thereto;

15. Fig. 15 illustrates a vamp unit consisting of two tongues connected by straps; and

Fig. 16 is a side elevational view of a pair of lasts carrying insoles with the straps of the unit of Fig. 15 attached thereto.

20. The application of the invention to the manufacture of shoes having full uppers will now be described with particular reference to Figs. 1 to 8, inclusive, of the drawings.

A pair of complete uppers 20 provided with 25 elastic box toe linings 21 (only one shown) is laid face to face with the outer surfaces in contact and united at the edges by a row of stitches 22 along the lasting margins. The united right and left uppers are then turned to expose the

30. outer surfaces, and the heel counters applied in the usual manner to the closed heels. Lasts 25 to which insoles 26 are tacked or otherwise secured, are then inserted into the uppers, as shown in Figs. 3 and 4. Prior to the insertion of the

35. insoles 26 are treated along the bottom edges with a suitable adhesive such as pyroxylin or liquid plastic cement or thermoplastic cement. When pyroxylin cement is employed, it is activated by an acetone solution before the lasts are inserted. If a thermoplastic cement is employed, it is activated by heat at a later stage in the process.

The pulling over of the uppers is preferably 45. though not necessarily performed by the use of an appropriate machine. The numeral 30 (Fig. 5) designates a very simple mechanism for the purpose. The pulling over in the machine 30 is performed by a looped constricting strand 31 of wire or suitable strong and flexible material.

50. The united uppers on their respective lasts are so presented to the machine that the loop portion of the strand seats in the V-groove 32 at the junction of the uppers. The machine 30 here shown comprises a pair of tables 33 spaced apart, legs 34 on which the tables 33 rest, and a

55. wiping element 35 which is caused to move back and forth across the top of the tables 33.

shaft 35 to which the ends of the strand 31 are secured. Fixed to the adjacent edges of the tables 33 are journal bearings 36 which receive the ends of shafts 37 carrying pulleys or grooved rollers 38 over which the strand 31 is guided. These pulleys 38 are arranged to cause the crossing point of the strand to be located at the desired point relative to the shoe and, to accommodate shoes of different sizes, the shafts 37 may be mounted in adjustable bearings if desired. The shaft 35 is rotatably supported in journal bearings 40 mounted on two of the legs 34 and carries at one end a disk 41 provided with a handle 42 and at the other end a ratchet 43. The lasts 25 carrying the uppers 20 are supported on the tables 33 with the strand 31 in the space 32 (see Fig. 5). The strand 31 crosses just below the ball portions of the vamps (Fig. 6) so that, when the shaft 35 is rotated in one direction (counterclockwise in Fig. 5), the strand is tightened and constricted about the united margins of the uppers, whereby the uppers are pulled over the lasts and the margins are drawn or wiped into contact with the adhesive bearing surfaces of the insoles 26. A pawl 44, carried by one of the legs 34, engages the ratchet 43 and thus holds the strand 31 tightened until the margins of the uppers have adhered firmly to insoles 26. In order to wipe the margins over the insoles at the shank, spools 39 of rubber or similar material are slipped along the strand so that when the strand is tightened, the spools 39 will be located as in Figs. 5 and 6.

The two lasts 25, carrying the uppers 20 thus attached to the insoles 26, are then mounted in a machine 45 by which the heel seats and shanks of the uppers are pulled over and attached to the insole and the lasting of both shoes completed. The machine 45 comprises a post 46 on which are supported a pair of arms 47 and 48 and a wiping device 49. The device 49 comprises a pair of wipers 50 which may be solid rubber or inflatable bags, pivotally supported at one end upon a sleeve 51 through which the post 46 passes. The wipers 50 are yieldably held in contact with each other as by a bolt 52 passed through both wipers 50, a coil spring 53 and a crank 54 threaded on one end of the bolt 52, the other end being fixed in one wiper 50. The tension of the spring 53 between the crank 54 and the other wiper 50 is regulated by the crank 54 so that the wipers are yieldably advanced toward each other to pull over the margins of the heel seats and shanks and wipe them against the adhesive coated surfaces of the insole 26. The lasts 25 are held in the machine 45 by the arms 47 and 48 between which the lasts are positioned as shown in Fig. 7. The arm 47 rests upon a collar 55 fixed on the post 46. The arm 48 carries a pinion 56 which meshes with a rack 57 on the post and which is rotated by a crank 58 to resist separation of the lasts during the wiping operation. The sleeve 51 is yieldably held in position on the post 46 by springs 59 and collars 60 so that the wipers engage both uppers.

The lasted uppers and insoles are at this stage joined to form two completely lasted shoes still connected at the forepart. The connection at the forepart is now severed, preferably by a knife at the space 32, and the making of the shoes is completed separately in any well known manner.

If it be desired that the finished shoes be provided with welts, a V-shaped strip 65 is inserted in the space 32 before pulling over the foreparts of the uppers in the machine 30 (see Figs. 9 and

10). The contacting surfaces of the strip 65 and the uppers 20 are joined by a suitable adhesive. The strand 31 seats the strip 65 in position when the pulling over of the foreparts previously described starts. Those surfaces of the upper which contact with the strip 65 are preferably roughened before adhesive is applied.

This invention is applicable to the manufacture of scuffs and other shoes having an upper 10 consisting of a vamp alone or in combination with a separate quarter. As shown in Figs. 11 and 12, two vamps 70 are superimposed with the outer surfaces in contact and joined by a line of stitching 71 along the inner edges of the lasting margins. The vamps 70 are then turned 15 and lasts 75 carrying insoles 76 inserted. A strand 77, similar to the strand 31 previously described, is employed to pull over the margins of the vamps and attach them to the outer surfaces of the insoles which have previously been provided with adhesive coatings. The vamps 70 are separated and the shoes completed independently.

If shoes having separate vamps and quarters are desired, the quarters 80 are prepared as shown 25 in Figs. 13 and 14. The quarters 80 are joined with the outer surfaces in contact by a line of stitching 81 along the edges of the lasting margins and wrapped around lasts 85 to which have been attached the insoles 76 carrying the vamps 70. The lasts 85 may be truncated, the foreparts being removed so that the toe portions of the insoles 76 with the vamps 70 are free. The insoles and quarters are assembled on the lasts and secured by tacks or the like in the well known manner. A strand 87 is employed to pull over the margins of the quarters 80 and attach them to the insoles in the same manner as are the vamps 70 treated. The quarters 80 are then 30 severed and the shoes suitably completed independently. It will be understood, however, that this operation may be reversed and the insoles 76 secured to the quarters before assembly with the lasts 75 or that the quarters may be attached to insoles carrying uppers of other types than that described or carrying no uppers whatsoever.

This invention is also applicable to the lasting of shoes, e. g., sandals whose forepart uppers each comprises a tongue and a plurality of straps connecting the tongue with the insole. Heretofore the straps have been inlasted and secured separately to the insoles, which has required the expenditure of considerable time and labor and much skill in order to provide equal stretch of the several straps. Figs. 15 and 16 illustrate one way of employing this invention in lasting shoes of this type. Two tongues 90 are joined by a plurality of straps 91 to form a pocket, the straps varying in length as required by the finished shoes. Lasts 95 provided with insoles 96 are inserted into the pocket thus formed, with the tongues 90 resting on the cones of the lasts. The straps 91, which as shown in Fig. 16 extend over the toes of both lasts, are pulled over the insoles 96 and secured thereto by a strand 97 in the manner previously described. The portions of the straps thus brought into contact with the insoles 96 are secured thereto by adhesive or other means in the well known manner. The 40 straps are severed along the line taken by the strand 97, and the shoes completed independently in the manner desired.

From the preceding description, it will be noted that the essence of this invention resides in the 45 simultaneous lasting of a pair of shoes. Several

ways of carrying out this invention have been disclosed as by forming the uppers of the two shoes (either complete uppers, vamps or quarters) as a single unit, assembling said unit with both lasts, pulling over the unit and attaching it to the insoles and severing the unit between the insole attached portions thereof. The pulling over and attaching of this unit are described as performed by a constricting strand of wire or any other strong and flexible material suitable for the purpose actuated by a mechanical means, but obviously means other than constrictive strands, for instance, suitably actuated wiper-plates or the like, might be employed, and the strands or other devices may be actuated manually. Moreover, when making shoes having full uppers, the foreparts of the shoes are first lasted, and then the quarters and shanks are simultaneously lasted before the foreparts of the two shoes are separated.

While several embodiments of the invention have been shown and described in detail, it will be understood that the invention is not limited thereto and that other embodiments thereof may be made without departing from the spirit and scope of the invention as set forth in the following claims.

I claim:

1. A machine for simultaneously pulling over the quarters and shanks of a pair of lasted shoes, the vamps of which shoes form a unit into which the toes of the lasts and the shoe insoles are inserted, comprising a pair of arms which engage the lasts and hold them in position and a wiping

device which simultaneously engages the entire lasting margins of the quarters and shanks of both shoes.

2. A machine for simultaneously pulling over the quarters and shanks of a pair of lasted shoes, the vamps of which shoes form a unit into which the toes of the lasts and the shoe insoles are inserted, comprising a pair of arms which engage the lasts and hold them in position and a wiping device which simultaneously engages the entire lasting margins of the quarters and shanks of both shoes, said device comprising a pair of wipers, each pivotally mounted at one end and formed to engage one-half the lasting margins of the quarters and shanks of both shoes, and means for yieldably advancing the wipers toward each other.

3. A machine for simultaneously pulling over the quarters and shanks of a pair of lasted shoes, the vamps of which shoes form a unit into which the toes of the lasts and the shoe insoles are inserted, comprising a pair of arms which engage the lasts and hold them in position and a wiping device which simultaneously engages the entire lasting margins of the quarters and shanks of both shoes, said device comprising a pair of wipers, each pivotally mounted at one end and formed to engage one-half of the lasting margins of the quarters and shanks of both shoes, a bolt extending transversely through said wipers, a spring encircling said bolt and a handle by which said spring is pressed against one wiper to advance it toward the other wiper.

MICHELE CUOZZO.
